UNITED STATES PATENT OFFICE.

ISRAEL KUSSNER, OF NEW YORK, N. Y.

STEEPLECHASE GAME.

Application filed June 2, 1925. Serial No. 34,375.

To all whom it may concern:

Be it known that I, ISRAEL KUSSNER, a citizen of the United States, residing at New York, in the county of New York and 5 State of New York, have invented certain new and useful Improvements in Steeplechase Games, of which the following is a specification.

This invention relates to games and toys 10 to a novel and improved steeplechase, embodying a number of freely supported objects such as a horse and a rider, suspended above a rotatable table or disc so that when the latter is rotated, the said objects will be 15 caused to pass over obstructions such as hurdles, stone walls and trees.

One of the objects of my invention is to provide a game embodying a wire frame and a rotatable disc or turn table, including 20 provision for hingedly supporting a plurality of objects, such as horses and riders, which are caused to encounter obstructions on the turn table as the latter is rotated.

25 In order to more fully understand and appreciate my invention, reference is had to the accompanying drawings, showing a preferred embodiment thereof, wherein,

The single view shows a perspective view 30 of the game.

It will be seen that 5 designates the base of a polygonal shaped frame, preferably constructed of wire. A series of upwardly extending rods 6, also constructed of wire, 35 are bent inwardly as at 7 and looped as at 8 to form an eye, one end of the said rod 6 terminating in a top disc 9. The respective wires 6 are looped as at 10 about the bottom frame 5 and extend inwardly and upwardly 40 as at 11 and terminate in a bottom disc 12, for a purpose presently to appear. The base and the rods above referred to constitute an open frame or guard for a vertical spindle and a turntable, on which a number of ob- 45 structions, such as hurdles, stone walls, and other objects appear.

Centrally of the wire frame, I provide a flat disc 13 having a hub 14, which constitutes a bearing for the lower end of a vertical spindle or rod 15. Mounted on the rod 50 is a turntable 16 on which the obstructions, above referred to, are positioned. The spindle 15, of course, extends through the top and bottom discs 9 and 12, and attached 55 to the top of the spindle is a turning knob 17, whereby the turntable may be rotated

on the bearing. The lower end of the spindle 15 is preferably pointed so that upon the rotation thereof and the turntable 16, mounted thereon, the latter will dip during 60 its revolution.

Supported from the respective eyes 8 of the vertical rod 6, and substantially intermediate the inwardly extending portion 7 thereof, are a plurality of suspended rods 18, on the lower ends of which are mounted the miniature horses and the riders 19. The upper ends of the rods 18 are loosely connected to the eyes 8 and the lower ends thereof to the detachable miniature objects 70 19 so that when the latter encounters or engages one of the obstructions, such as the hurdles 20 and wall 21, the said objects will fall from the rods. By reason of the rotation of the turntable 16, which will have the 75 tendency to dip, certain of the objects will pass over the obstructions, whereas others will strike the obstructions. In this manner it will be seen that a novel and interesting game is afforded wherein certain 80 players electing certain of the objects 19 may play the game, it being assumed that the objects remaining suspended after the turntable has been rotated, may constitute the winners or the losers of the game as the 85 case may be.

While I have illustrated and described my invention with some degree of particularity, I realize that in practice various alterations 90 therein may be made. I therefore reserve the right and privilege of changing the form of the details of construction or otherwise altering the arrangement of the correlated parts without departing from the spirit of the invention or the scope of the appended 95 claims.

Having thus described my invention, what I claim as new, and desire to secure by United States Letters Patent is:—

1. A toy or game of the class described 106 comprising an open frame, a plurality of detachable units suspended from the top of the frame, a rotatable shaft and support therefor mounted centrally of the frame, a turntable rotatable with the shaft and ob- 105 structions on the turntable for engaging said detachable units.

2. A toy or game of the class described 110 comprising a polygonal open frame having inwardly extending rods at the top and bottom terminating in a top and bottom disc, a plurality of detachable units carried by the

top rods, a rotatable shaft passing through the discs, a support for the lower end of the shaft, a turntable rotatable with the shaft, said turntable having obstructions for engaging the said units.

3. A toy or game of the class described comprising an open wire frame having a polygonal base, a series of vertical rods connected to the base, said rods being bent inwardly at their top and bottom and terminating in a top and bottom disc, a plurality

of objects loosely suspended from the inwardly bent top portion of the rods, a vertical shaft and a supporting base therefore axially of the wire frame, said shaft passing through the discs and a turntable having obstruction thereon carried by the shaft, said obstructions engaging the suspended objects when the turntable is rotated. ¹⁵

In testimony whereof I affix my signature.

ISRAEL KUSSNER.
